UNITED STATES PATENT OFFICE.

WILLIAM REGINALD RIDINGS, OF MANCHESTER, ENGLAND.

ARC-LAMP.

1,052,425.

Specification of Letters Patent.

Patented Feb. 4, 1913.

Application filed October 5, 1912. Serial No. 724,163.

To all whom it may concern:

Be it known that I, WILLIAM REGINALD RIDINGS, subject of the King of Great Britain, and residing at Manchester, in the county of Lancaster, England, have invented certain new and useful Improvements in Arc-Lamps; and I do hereby declare the following to be a full, clear, and exact description of the invention, such as will enable others skilled in the art to which it appertains to make and use the same.

This invention relates to improvements in arc lamps of the magazine type and in particular to lamps of this type in which the carbons are inclined toward each other, and both point in a downward direction, the arc being formed at their lower extremities. In this type of arc lamp it has been proposed to feed the electrodes simultaneously forward by a device attached to a carrier which is alternately raised and lowered by an endless sprocket chain so that the said device is caused to engage successively with each pair of carbons in the magazine. It has also been proposed to provide two tubular carbon guides partly cut away longitudinally to expose a portion of the end of the carbons therein and situate an endless band, having laterally projecting tappets, in such a position that the said tappets bear on the exposed portions of the end of the carbons and feed the same when the said band is automatically moved by suitable means. The said tappets were however liable to slip off the end of the carbons if the latter were subjected to unusual frictional resistance from any cause.

The object of my invention is to dispense with the said device and carrier and thereby simplify and improve the feeding mechanism of this type of lamp, and at the same time obviate the above named defect. I attain these objects by the mechanism illustrated in the accompanying drawing, in which—

Figure 1 is a front view, Fig. 2 a side view, and Fig. 3 a sectional plan on line A—A of Fig. 1, Fig. 4 is a detached sectional front view and Fig. 5 a detached side view of one embodiment of my invention.

Similar letters refer to similar parts throughout the several views.

In carrying out my invention and referring to the figures generally each magazine is formed of a flat rectangular receptacle *a* open at opposite sides. One of the said open

sides serves for charging the magazine with carbons as hitherto. A plate *b*, facing the other side, but at a distance approximately equal to the thickness of a carbon, away from the same, is secured to the top and bottom of the receptacle, by means of brackets *c* which project at right angles from the same in a direction parallel to the plate *b*. A slot *d* which is open equally at the upper and lower end of the receptacle is thus formed.

A pitch chain *e* is so mounted on two pitch wheels *f* and *g* that one side comes between the receptacles and in alinement with the slots *d*. The axis of the upper pitch wheel *f* is situated above the upper ends of the said receptacles and the axis of the lower pitch wheel *g* slightly below the lower ends of the same. To each of two pivots of the chain at equal distances from each other is secured a pin *h* which projects through the slots *d*. The upper pitch wheel *f* is driven by a worm gear *i*, *k* which may receive its motion from a ratchet and pawl operated by a shunt coil or from a small motor (not shown). The carbon holders *l* at the base of the lamp are in alinement with the slots *d*. A bar *n* is secured to a shaft *o* which has also secured to it an arm *p* under the influence of a spring *q*. The bar *n* serves to force carbons toward the said slots.

The above described mechanism operates as follows:—When the magazines *a* are charged the foremost carbons *r* are forced into the slots *d* and pressed against the plates *b*. On current being applied to the lamp, the said shunt coil or motor is actuated and the chain *e* thereby moved, one of the pins *h* on the same traveling downward in the slots *d* and the other pin *h* upward on the other side of the chain *e*. The pin *h* in the said slots presses the carbons *r* downward through the spring clutches *m*, and when the carbons *r* are fed sufficiently the arc is struck and the lamp continues to burn in the usual manner. The carbons *r* are fed downward when required by the pin *h* in the slots *d*. By the time the carbons *r* have been forced to the lower ends of the slots *d* by the pin *h* the latter has reached the end of its straight downward travel, and commences to move around the periphery of the lower pitch wheel *g*, the open slots *d* allowing this to take place. As soon as the pin *h* has left the said slots the next carbons *s* are forced into position by the bar *n* and the second pin *h*, which has

been passing over the periphery of the upper pitch wheel *f*, enters the open slots *d* at the top and proceeds to press the carbons *s* downward, until the ends of the now 5 used carbons *r* are forced out and a new arc has been formed with the new carbons *s*.

As will be readily understood the above 10 described mechanism may be applied to arc lamps having one or both magazines movable.

The faces of the plates *b* against which the carbons *s* press may have slight grooves *t* to guide the said carbons and the plates *b* may also be rounded off at their lower ends 15 to facilitate the exit of the pins *h* from the slots *d*.

I claim:

1. In an arc lamp, converging grooved guides, magazines adjacent to and in parallelism with the guides and adjacent the grooved side of such guides, a sprocket chain moving intermediate the guides and having one side in a plane with the interval between 20 the guides and the magazine and rods carried by the chain extending laterally there-

from proportioned to extend at all times between the guides and magazines.

2. In an arc lamp, converging grooved guides having their lower ends flared outwardly, a base connected with the lower outwardly extending ends of the guides, magazines spaced from the guides, each in a plane with one of the guides and adjacent the grooved side of such guide, a sprocket chain moving substantially midway between 35 the guides and having one side in a plane with the interval between the magazines and the guides, a rod carried by and extending laterally from the chain and proportioned to extend at all times between 40 the guides and magazines and to pass between the outwardly flared ends of the guides, and means to move carbons within the magazines.

In testimony whereof I have affixed my 45 signature in presence of two witnesses.

WILLIAM REGINALD RIDINGS.
